United States Patent Office

Des. 188,739
Patented Aug. 30, 1960

188,739

PHOTOCOPY MACHINE

Kenneth R. Reick, 634 S. Main St., Lombard, Ill.

Filed Aug. 5, 1959, Ser. No. 57,070

Term of patent 7 years

(Cl. D61—1)

FIG. 1

FIG. 2

FIG. 3

Figure 1 is a perspective view of the photocopy machine showing the top, left side and front thereof, the right side being substantially the same as the left side;

Figure 2 is a top plan view of the machine; and
Figure 3 is a rear elevational view of the machine.
I claim:

The ornamental design for a photocopy machine, substantially as shown and described.
